UNITED STATES PATENT OFFICE.

JOHN McDougall, of Lehigh, Iowa.

CLOTHES-DRIER.

SPECIFICATION forming part of Letters Patent No. 269,819, dated December 26, 1882.

Application filed April 29, 1882. (No model.)

To all whom it may concern:

Be it known that I, JOHN McDougall, a citizen of the United States, residing at Lehigh, in the county of Webster and State of Iowa, have invented certain new and useful Improvements in Clothes-Driers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a perspective view of this device. Fig. 2 is a vertical central section of device shown in Fig. 1.

This device belongs to that class of inventions known as "clothes-driers;" and the points or features of novelty consist in the details of the construction and combination of the several parts, all as will now be more fully set out and explained.

The upright or stem to which the arms carrying the clothes are attached consists of several sections or parts—namely: the base A, on which is placed section B, and above this the section C, while between sections B and C comes the annulus D, capable of revolving in the groove b; and above C is placed the top section or piece, E, while between C and E is placed the upper and smaller annulus, F, adapted to revolve in the groove or channel c between the ends of C and E, as D revolves between the ends of B and C. The base and all the sections, being made hollow, are readily secured together in position now shown in the drawings by means of the headed bolt or rod G, passing down through them and fastened tightly in place by nut g in the base. The arms H and H, which are designed for the clothes-support, are detachably hinged in the revolving sections D and F. This arrangement is now shown as carried out by placing the curved or hooked end h of each arm in the eye d' of any one of the lugs or ears d of section D or in the eye f' of any one of the lugs or ears f of section F. This curved end acts as a hinge on which to move the arm up or down, according as it may be designed to open it for use or close it when not in use. Said end also serves as a stay to retain the arm in

the eye against displacement under any of the ordinary conditions of use.

The lower revolving annulus, D, may be of somewhat larger diameter than the revolving annulus F. Between the ears on each section the periphery of each annulus may be hollowed out. This configuration of the lower section will afford convenient notches d'', into which the arms of the upper section may fall when they are not in use. In the outer curved ends, h', of each arm is fastened the cord or wire h''. If wire is used, its own rigidity will keep it in place when the arm is hanging down. If cord is used, convenient arrangement can be made to fasten it to the arm. When the arm is turned up and extended to use, the end of the cord or wire h'' is brought into a notch, h''', in one of the lugs d'' or f'' on the upper side of the section or revolving annulus D or F, and being pressed down into said notch is brought taut, while the knob h⁴ on the end of the wire or cord serves to retain it in position. As few or as many of the arms may be used at one time as may be desired. The relative arrangement of the two movable sections and the arms is such that the clothes on the upper arms will not be in the way of those on the lower; or the smaller pieces can be put on the upper arms, and so prevent any interference with the lower. Any convenient number of revoluble annuli or disks can be used, so that instead of two parallel sets of clothes-arms, there may be one, or three, or more.

The device is very cheaply and easily made, and is very durable in use. As the arms are rotated by the action of the wind, there is no danger of having the clothes torn by high gales.

Having thus described my invention, what I consider new, and desire to secure by Letters Patent, is—

1. In combination with the stem A B C E, as described, and revolving clothes-arms, carriers D and F, having depending ears d and f and upwardly-projecting lugs d'' and f'', the adjustable and detachable clothes-arms H, having hooked ends h to engage on said ears, and provided with a line or wire to engage upon said lugs d'' f'' and hold the arm extended, substantially as set forth.

2. The stem composed of sections and hav-

ing grooves *b* and *c*, and held together by headed bolt *G* and nut, combined with annuli *D* and *F*, each having ears *d f* and lugs *d' f'*, and detachable and adjustable arms *H*, having hooked ends *h* and outer curved ends, *h'*, and provided with wire or line *h''*, all substantially as described.

3. The clothes-arm *H*, having projections *h'* at its outer end and line or wire *h''* attached thereto, and the inner hooked end, *h*, combined with the support, having an ear below and an up-

ward projection, whereby said arm can have vertical motion on said support or be secured in position for use, all substantially as set forth.

In testimony whereof I affix my signature in presence of two witnesses.

JOHN McDougall.
